UNITED STATES PATENT OFFICE.

JAMES E. GILLESPIE, OF WARWICK, NEW YORK, ASSIGNOR TO THE
FABRIC FIRE HOSE COMPANY, OF SAME PLACE.

CIRCULAR LOOM.

SPECIFICATION forming part of Letters Patent No. 361,758, dated April 26, 1887.

Application filed August 12, 1882. Serial No. 69,199. (No model.)

To all whom it may concern:

Be it known that I, JAMES E. GILLESPIE, of Warwick, in the county of Orange and State of New York, have invented a new and useful Improvement in Circular Looms, of which the following is a specification.

My invention relates more particularly to looms for weaving multiple-fabric hose composed of two plies, the wefts of which run in opposite spiral directions through the warps, such hose being the subject of my Letters Patent No. 268,366, dated November 28, 1882; but certain features of the invention may be embodied in looms for weaving two-ply circular fabrics of other kinds.

The invention consists in certain combinations of circular shuttle-raceways, shuttles running thereon, and mechanism for driving said shuttles, and in certain combinations of shuttles, shuttle - driving mechanism, raceways, warp-shedding mechanism, and warp guide-rings, all substantially as hereinafter described and claimed.

In the accompanying drawings, Figure 1 represents a vertical section of a loom embodying my invention adapted for weaving the two-ply fabric hose, which is the subject of the Letters Patent hereinabove referred to. Fig. 2 represents a horizontal section on the dotted line α α , Fig. 1, certain parts being removed. Fig. 3 represents a detail view, looking from the center of the loom outward, of a pair of shuttles, with their raceways and driving mechanism; and Fig. 4 represents an elevation of part of the mechanism for operating the heddles. Fig. 5 is a plan view of part of the shuttle mechanism corresponding with Fig. 1, adapted for driving the upper shuttles in one direction. Fig. 6 is a plan view illustrating a modification of the parts shown in Fig. 5 for driving the said shuttles in the opposite direction.

Similar letters of reference designate corresponding parts in all the figures.

The frame of the loom may be of any suitable construction, but as here shown comprises standards or uprights A, upper and lower circular plates or rings, A' A², and upright bars or slats A³, connecting the upper and lower plates or rings, A' A², and formed integral therewith.

I will first proceed to describe the shuttles and their raceways and driving mechanism.

B designates the upper shuttles and B' the lower shuttles. One upper and one lower shuttle constitute a pair, and the loom may be provided with a single pair of shuttles; but for rapid work I prefer to employ two pairs of shuttles, as here shown. The two upper shuttles constitute what I term a "set of shuttles," 60 and the two lower shuttles another set; but each set, instead of two shuttles, might comprise three or more shuttles, if desired.

As here shown, each shuttle B B' is made in the form of a triangular frame, in which is 65 journaled the west bobbin B²; but the shuttles may be of any other suitable form.

The shuttle-raceways are here represented as formed by three tiers or series of grooved rollers, there being an upper series, C, a middle series, C', and a lower series, C², all of which are adapted to turn freely on journals or studs fixed in the upright bars or slats A³, and the shuttles each have grooves a, which engage with the innermost flanges of the said 75 grooved rollers, as best shown in Fig. 1.

The upper set of shuttles, B, are arranged between and in engagement with the tiers or sets of guide-rollers C C', and the lower shuttles, B', are arranged between and in engagement with the two tiers or sets of guide-rollers C' C². The shuttles are therefore supported both at the top and bottom, and hence their inner ends are kept in the same horizontal plane, as the shuttles move and cannot drop 85 down.

D designates a piece of hose in the process of weaving, and E designates a central tube or hollow post, through which the completed hose may be delivered. The take-up might, 90 however, be upward instead of downward.

F designates a tubular shaft surrounding the tube or post E, and having at its lower end a bevel-wheel, F'.

G designates a horizontal counter driving-shaft provided with fast and loose pulleys, G' G², over which a driving-belt may be passed, and also carrying a bevel-wheel, G³, which engages with the wheel F', and through it rotates the tubular shaft F. The counter-shaft G also carries a bevel-wheel, G⁴, at its outer end, which engages with a bevel-pinion, H,

and through said pinion operates a vertical shaft, H', on which the pinion H is secured, as best shown in Fig. 2.

At the upper end of the tubular shaft F is a cross-bar or plate, I, which is rotated with the shaft, and the form of which is shown in Fig. 2. Upon each end of the plate or bar I, at its upper side, is pivoted a small roller, b, which fits between two corresponding rollers, c, pivoted to each of the lower shuttles, B', as seen in Fig. 3. The rollers c on each shuttle rest upon and straddle the roller b on the plate or bar I, and as the said plate or bar turns or rotates in a horizontal plane the lower 15 shuttles are carried with it.

The rollers b c, arranged as shown, for imparting motion to the shuttles from the rotary plate or bar I, are desirable, because they provide for giving a positive motion to the shuttles, and the warp-threads will pass between the rollers, or the rollers will pass over the warp-threads as the shuttles are moved.

The upper shuttles, B, are each provided with a pair of rollers, c, in their upper sides, 25 and above the upper tier of guide-rollers C is a horizontal toothed ring, J, which has a circumferential rib fitting in a groove, d, in the upper plate or ring, A', as shown. By this rib and groove the ring J is supported and 30 maintained in a horizontal plane and allowed to rotate freely.

Depending from the ring J are hangers or brackets e, which carry rollers b, which fit between the rollers c on the upper shuttles, and 35 when the ring is rotated it carries the upper set of shuttles, B, with it in the same manner that the plate or bar I carries the lower shuttles, B'.

Above the ring J, in a fixed bearing, A*, 40 provided in the plate A', there is arranged a horizontal shaft, K, which receives a rotary motion from the vertical shaft H', through bevel-wheels f f', and which has at its inner end a bevel-pinion, f'', which engages with and 45 drives the toothed ring J, as shown in Figs. 1, 5, and 6.

It may be understood that both the upper and lower shuttles derive their circular motion around their respective raceways from 50 the one shaft G, and that the upper shuttles may move either in the opposite direction to or in the same direction as the lower ones, according to the gearing of the shaft H'. If the bevel-wheel f engages with that, f', on that 55 side of the shaft H' nearest to the ring J, as shown in Figs. 1 and 5, the upper shuttles will move in the opposite direction to the lower ones; but if the bevel-wheel f engages with that, f', on the side of the shaft H' farthest 60 from the ring J, the direction of the motion of the upper shuttles and the lower ones will be the same.

I will now proceed to describe the heddles and the mechanism operating them, and the 65 guides for the warps.

The heddle-frames are arc-shaped, as shown in dotted lines in Fig. 2, and are here shown as

arranged in four groups circumferentially about the loom. Each group comprises four heddle-frames, L L' L'' L''', which are connected by rods g g' g'' g''', with a bar or plate, M, secured upon a shaft, N, arranged near the bottom of the loom. This bar or plate constitutes two arms projecting from the shaft in opposite directions. There are four shafts N, one for operating each group of heddles.

Surrounding the loom are three stationary guide-rings, O O' O'', for the warps. The upper ring, O, guides the warps which are interwoven with the wefts carried by the upper 80 shuttles, B, to form the inner ply of the hose, and the lower ring, O'', guides the warps which are interwoven with the wefts carried by the lower shuttles, B', to form the outer ply of the 85 hose. The middle or intermediate ring, O'', guides the warps which are woven into and incorporated with the two plies for securing them together. The warps from the upper and lower guide-rings, O O'', pass through and 90 are controlled by the heddles in the first and third frames, L L'', and thence pass through the slots between the bars A''. The warps from the middle or intermediate ring, O'', pass through the heddles of the second and fourth frames, L' L''', and thence also pass between the 95 slats or bars A''', and these warps are incorporated with and woven into both plies of the hose; hence it is necessary that the second and fourth heddle-frames, L' L''', of each group should have a greater length of movement 100 than the frames L L'', and to secure this the rods g g''', for operating said frames L L'', are connected to the plates or bars M at a greater distance from the shafts N than the rods g g'', which operate the first and third heddle-frames, L L''.

Upon each of the shafts N is secured a pinion, h, through which it may be turned, and near the bottom of the loom are two horizontal bars or rods, P, which cross each other at right angles and each of which is offset to one side, as shown in Fig. 2, so as to pass the shaft F.

To the ends of the bars P are secured racks i, which engage with and rest upon the pinions h, and which are sunken or recessed, so that 115 they will remain in engagement with the pinions h, and as the bars P are reciprocated the shafts N, which are diametrically opposite each other in the loom, will be turned one-half a revolution alternately in opposite directions, 120 and will thus simultaneously shift the groups of heddles which are diametrically opposite each other.

One of the rack-bars, P, is slightly bent or offset upward, so that it may pass over the 125 other bar, as shown in Fig. 1.

Upon each bar P are journaled two rollers, j; and Q designates a single cam on the shaft F, which operates upon the rollers j and serves to impart the proper reciprocating motions to 130 the bars P. The form of the cam Q is shown in Fig. 2.

A loom having my improvements applied may be used for weaving a single-ply hose,

when one set of warps are omitted, in which case the shuttles belonging to that set of warps may be allowed to remain in their raceways, and will run therein in the same way as they 5 do in weaving, but without producing any effect on the warp which is in the loom and which is woven with the wefts from the other set of shuttles.

What I claim as my invention, and desire 10 to secure by Letters Patent, is—

1. The combination of two complete circular raceways, co-operating shuttles, one or more on each of said raceways, and mechanism, substantially as described, for imparting continuous motion to all the shuttles simultaneously, 15 each on its own raceway, substantially as and for the purpose herein set forth.

2. The combination, with two complete circular raceways, of co-operating shuttles, one 20 or more on each of said raceways, and mechanism, substantially as described, for imparting continuous motion to the shuttles on the two raceways simultaneously in opposite directions, substantially as and for the purpose 25 herein set forth.

3. The combination, with two complete circular raceways, of co-operating shuttles, one or more on each of said raceways, mechanism, substantially as described, for imparting continuous motion to the shuttles about the two 30 raceways, and shedding mechanism common to the shuttles on both raceways, all substantially as herein described, for the purpose of weaving a two-ply circular fabric.

35 4. The combination, with upper and lower raceways and shuttles or sets of shuttles, of a

vertical shaft and devices connected therewith for driving the lower shuttle or shuttles, a toothed ring arranged above the shuttles and devices connected with said ring for driving 40 the upper shuttle or shuttles, a driving-shaft, and mechanism through which said driving-shaft rotates said vertical shaft and said ring, substantially as specified.

5. The combination of upper and lower shuttles, mechanism for driving them, and raceways composed of an upper tier of guide-rollers with which the upper shuttle or shuttles engage, a lower tier of guide-rollers with which the lower shuttle or shuttles engage, and an 50 intermediate tier of guide-rollers with which both the upper and lower shuttles engage, and supports for said guide-rollers, substantially as specified.

6. The combination of the upper and lower 55 shuttles, B B', each provided with a pair of rollers, c, the rotary plate or bar I, and rotary ring J, and rollers b on said plate or bar and ring, and mechanism for producing the rotary motion of said plate or bar and ring, substantially as specified.

7. The combination of two shuttles or sets of shuttles, mechanism for driving the same, warp-shedding devices for the warps for two plies, and three guide-rings, two of which 65 guide separate warps for the two plies, while the third guides warps for weaving into both plies, substantially as herein described.
